(57) **CLAIM**

The ornamental design for a halter-neck fan as shown and described.

DESCRIPTION

FIG. 1 is a front, top, left side perspective view of a halter-neck fan of my design;
FIG. 2 is a rear, bottom, right side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarged view of area 9 circumscribed in FIG. 1; and,
FIG. 10 is an enlarged view of area 10 circumscribed in FIG. 2.
The broken lines encircling the enlarged detail views are for annotative purposes that form no part of the claimed design.

1 Claim, 10 Drawing Sheets
